Des. 218,861
Patented Sept. 29, 1970

218,861

TAPE DISPENSER

Charles Castelli, New Brunswick, and Earl E. Hoyt, Northvale, N.J., assignors to Johnson & Johnson, a corporation of New Jersey

Filed June 3, 1969, Ser. No. 17,490

Term of patent 14 years

Int. Cl. D19—02

U.S. Cl. D74—1

FIG. 1 is a perspective view of the tape dispenser embodying our new design;

FIG. 2 is a front elevational view;

FIG. 3 is a side elevational view;

FIG. 4 is a top plan view;

FIG. 5 is a side elevational view showing the side opposite that shown in FIG. 3; and

FIG. 6 is a rear elevational view thereof.

We claim:

The ornamental design for a tape dispenser, substantially as shown.
